WINDOW SCREEN

Patsey Morfy, Tamaqua, Pa., assignor of one-fourth to Emanuele Tunno and one-fourth to John Ciccozzi, both of Tamaqua, Pa.

Application February 7, 1942, Serial No. 429,911

1 Claim. (Cl. 160—376)

This invention relates to a window screen and has for the primary object the provision of a device of the above stated character which will be self-adjusting to a window frame and when adapted thereto will provide a positive exclusion of insects and the like and will be extremely durable and may be manufactured and sold at a low cost.

Another object of this invention is the provision of a yieldable spring influenced member secured to one of the vertical sides of the screen frame for a limited sliding movement in relation thereto for permitting the screen frame to be easily and quickly applied and removed from the window frame and acting to sustain the screen frame tightly within the window frame against accidental displacement or from movement relative thereto as to present cracks through which insects might pass.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawing, in which

Figure 1 is a side elevation, partly in section, illustrating a window screen constructed in accordance with my invention.

Figure 2 is an edge elevation illustrating the device.

Referring in detail to the drawing, the numeral 5 indicates a rigid frame constructed of any material suitable for the purpose and consisting of upper and lower rails 6 and 7 and vertical end rails 8 and 9. Said rails may be secured to each other in any well known manner so as to prevent them from having relative movement. The rails each has a rabbeted face forming a seat extending entirely about the frame in which may be secured the edges of a foraminous material 10 employed for the closing of the frame.

Suitable beading or finishing strips 11 are secured to the rails to assist in retaining the edges of the foraminous material within the seat.

The rail 9 is of less width than the rail 8 and is provided with an opening substantially intermediate its ends to slidably receive a bolt or like fastener 12. The bolt or like fastener mounts on the rail 9 for a limited sliding movement relative thereto a channeled member 13. The channeled member 13 provides to the rail 9 a yieldable extension. One end of the bolt 12 has threaded thereon a nut 14 which will permit the application and removal of the channeled member 13 when desired.

Secured to the rail 9 by screws or like fasteners 15, is a spring member 16 the ends of which bear against the channel member 13 for urging the

latter away from the rail 9. The channeled member is prevented from having complete separation from the rail 9 under the influence of the spring member 16, by the bolt 12. The spring member includes a substantially straight attaching portion 17 apertured to receive the fasteners 15 and also provided with an opening through which the bolt 12 extends. The spring member further includes substantially arcuately curved end portions 18 having riding contact with the channeled member 13.

Owing to the fact that the channeled member may be moved toward the rail 9 of the frame 5, will permit the latter to be easily placed within the supporting channels of a window frame and will automatically exert sufficient pressure of the screen frame against the window frame as to prevent accidental displacement of the screen.

In applying the window screen to a window frame, the channeled member is first brought into contact with a vertical channel of the window frame and by shoving the screen frame in the direction of said channel of the window frame, the spring 16 will yield and permit sufficient relative movement between the channeled member and the screen frame to allow the rail 8 to readily enter the opposite channel of the window frame and as soon as the pressure is released on the window screen the spring acts to bring about a tight fit between the window screen and the window frame. The removal of the window screen from the window is accomplished in a similar manner to that of applying the screen to the window.

While I have shown and described the preferred embodiment of my invention, it will be understood that minor changes in construction, combination and arrangement of parts may be made without departing from the spirit and scope of the invention as claimed.

Having thus described my invention, what I claim is:

In a window screen having a rigid frame closed by foraminous material and including end rails and upper and lower rails, a channeled extension member frictionally fitted to the frame to receive one of the end rails and end portions of the upper and lower rails for sliding movement relative to said frame, a headed bolt having the head thereof countersunk in the member substantially intermediate the ends of the latter and slidable through the last referred to end rail, a nut threaded on the bolt for limiting the sliding movement of the member and preventing its complete separation from the frame, and a bowed leaf spring including end portions bearing against the member adjacent the ends thereof and a substantially straight portion connecting the end portions and apertured to slidably receive the bolt and secured on the last referred to end rail at opposite sides of said bolt.

PATSEY MORFY.
